STOP MOTION RESETTING DEVICE

Alfred Crawford and Michael Antonevich, New Brunswick, N. J., assignors to The Crawford Manufacturing Company, Incorporated, New Brunswick, N. J., a corporation of New Jersey

Application October 21, 1949, Serial No. 122,684

11 Claims. (Cl. 66—166)

1

This invention relates to stop motions for knitting machines and more particularly to improvements in detector devices of the type adapted to interrupt operation of the machine upon appearance in the knitted product of defects such as holes, drop stitches, runs or the like.

A primary object of the invention is to provide a generally improved detector device of this character.

Another and more specific object is to provide a detector device comprising means readily and rapidly operative after the device has been actuated in performance of its normal function for resetting the detector element or elements to operative state, said resetting means being of particular value in connection with detector devices having multiple detector heads.

The invention resides further in certain novel structural and mechanical details hereinafter described and illustrated in the attached drawings wherein:

Fig. 1 is a fragmentary vertical sectional view of circular knitting machine provided with a detector device in accordance with the invention;

Fig. 2 is an enlarged side elevational and partial sectional view of one of the several detector heads included in said device;

Fig. 3 is a top plan and partial sectional view of the detector head;

Fig. 4 is a rear elevational view of the head;

Fig. 5 is a sectional view on the line 5—5, Fig. 2;

Fig. 6 is a side elevational view of a detector head illustrating a modification of the head shown in the preceding figures;

Fig. 7 is a fragmentary front elevational view of the head shown in Fig. 6;

Fig. 8 is a sectional view on the line 8—8, Fig. 6;

Fig. 9 is a fragmentary plan view of a detector device of the character shown in Fig. 1 but employing a modified form of detector head;

Fig. 10 is a side elevational and partial sectional view of the device shown in Fig. 9;

Fig. 11 is a sectional view on the line 11—11, Fig. 9;

Fig. 12 is an enlarged plan view of the detector head shown in Fig. 9;

Fig. 13 is a fragmentary plan view of the head showing certain of the elements in positions assumed after actuation of the head;

Fig. 14 is a side elevational view of the detector head shown in Fig. 12;

Fig. 15 is a vertical sectional view of the detector head;

Fig. 16 is a sectional view on the line 16—16, Fig. 15;

2

Fig. 17 is a longitudinal sectional view showing the elements of one of the detector fingers;

Fig. 18 is a plan view of a detector head in still another form;

Fig. 19 is a side elevational view of the detector head shown in Fig. 18;

Fig. 20 is a sectional view on the line 20—20, Fig. 19;

Fig. 21 is a vertical sectional view of the detector head shown in Figs. 18 and 19;

Fig. 22 is a sectional view on the line 22—22, Fig. 19;

Fig. 23 is a fragmentary sectional view showing elements of the device in different relative positions;

Fig. 24 is a fragmentary plan view corresponding to Fig. 9, but on a reduced scale, illustrating a detector device having a slightly modified form of retracting mechanism;

Fig. 25 is a side elevational view, partly in section, of a modified form of detector device within the scope of the invention; and

Fig. 26 is a plan view of the assembly shown in Fig. 25.

With reference to Fig. 1 of the drawings, 1 is the rotary needle cylinder of a knitting machine and 2 the knitted tubular fabric which passes downwardly from the needles 3 through the cylinder to the draw rolls 4. Supported on a rod 5 within the cylinder 1 and fabric 2 is the detector device forming the subject of the present invention.

This detector device comprises a cylindrical hub member 6 which is secured by a set screw 7 to the rod 5 and in which are adjustably secured a plurality of radially extending rods 8. The outer end of each of these rods lies in proximity to the fabric tube 2 and carries a detector head 9. In the present instance each head 9 comprises three detector fingers 11, 12 and 13, and in operation the outer ends of these fingers press lightly against the inner surface of the rotating fabric tube. The fingers are slidably supported in the head structure and are urged outwardly by resilient means (hereinafter more specifically described), so that when the end of one of the fingers encounters a hole of undue size in the fabric it will pass into such hole. The resulting lateral pull of the fabric on the finger will operate as hereinafter described to actuate the device to interrupt the operation of the machine.

With reference to Figs. 2 to 5 inclusive, which illustrate in detail one of the detector heads 9, the head comprises a base member 15 generally of channel form, as shown in Fig. 5, which is secured to the outer flat end of the associated sup-

porting rod 8 by means of screws 16 and 17. As shown in Fig. 2, the screw 16 is insulated from the base 15 by insulating sleeves and washers indicated at 18; and the screw 17 is similarly insulated by suitable insulating elements 19 from the supporting rod 8. The base 15 is insulated by the same means from the support 8.

Slidably mounted in the base 15 is a member 21, this member having at its rear end a depending arm 22 to which is secured a spring 23, the other end of this spring being anchored to the base 15. The spring thereby tends to retain the member 21 in an advanced position in the base as illustrated in Figs. 2 and 3. The member 22 may be retracted in the base 15 against the action of the spring 23, and a retracting rod 24 connected to the member 21 by means of a screw 25 is provided for that purpose.

Pivottally mounted upon the forward end of the member 21 through the medium of a screw 26 is an element 27, said element having an upwardly extending stem 28 in which are mounted detector fingers 11, 12 and 13. As shown in Fig. 2 each of these fingers is supported in a tubular casing, 29, 31 and 32 respectively, which are adjustably secured in the stem 28 by screws 33. In each instance a spring 34 associated with the finger tends to hold it in an extended position in which the finger projects well beyond the forward end of its tubular casing. In practice, and as illustrated in Fig. 1, these fingers will engage the inner surface of the tubular knitted fabric 2, the spring acting to hold the tips of the fingers in firm contact with the fabric.

Means is provided for retaining the element 27 in a predetermined normal position on the member 21, this means in the present instance consisting of the spring pressed ball and socket device illustrated at 35 in Fig. 2. In this normal position the fingers extend substantially radially with respect to the center of the hub member 6.

The forward end of the element 27 is centrally recessed, as shown in Fig. 3, and in normal position the said element under the influence of the spring 23 will rest against a pin 36 which extends upwardly from the base 15, the pin contacting the element 27 at the bottom of the recess 37 in the latter. When the element 27 is angularly displaced about the pivot 26 from the normal position, one of the smoothly rounded forward surfaces 38 at the sides of the recess will exert a camming action against the relatively fixed pin 36 which will cause a certain limited retractive movement of the member 21 in the base 15. The function of this limited retractive movement of the member 21 will be described below. A further retractive movement of the member 21, effected as described above by way of the rod 24 will bring the sides of the member 27 into engagement with one or other of a pair of relatively fixed abutments 39 and 41 which extend upwardly from and at opposite sides of the base 15, the resulting pressure upon the element 27 being sufficient to turn it on the pivot 26 back to the original or normal position from which it was displaced. In Fig. 3 the angularly displaced position of the element 27 is shown in dotted lines and it will be evident with this position of the element, that when the member 21 is retracted in the base 15, the side of the element will be brought into engagement with the abutment 39 which will then exert a camming action to return the element to the normal position.

The angular displacement of the element 27 will be effected when any one of the detector

5 fingers under the pressure of the associated spring 34 will pass through a hole in the fabric 2, the rotary movement of the tubular fabric then carrying the fingers laterally with resulting displacement of the element 27.

Within the structure of the head 9 is an electric switch comprising a fixed contact element 40 and a relatively movable contact 42. The element 40 is secured at the upper end of the screw 16 and is therefore insulated from the base 15 and electrically connected through the screw with the support 8. The movable element 42 is in the form of a lever pivotally supported upon a pin 43 extending upwardly from the base 15. A spring 44 exerts resilient pressure upon the element 42 to retain it in retracted position, as shown in Fig. 3, wherein it is disengaged from the contact element 40, the switch thereby being open. Depending from the member 21 is a pin 45 which, as best shown in Fig. 3, is in operative association with the rear end of the member 42 so that when the member 21 is moved rearwardly from the normal advanced position of that member the pin 45 will engage the inclined surface 46 of the element 42 to thereby turn the said element in counterclockwise direction as viewed in Fig. 3 with the result that the turned-down forward end of the element 42 will be brought into engagement with the relatively fixed contact element 40 thereby closing the switch. As previously set forth this switch closing operation will be performed by camming action of the element 27 against the pin 36 occurring when the element 27 is displaced angularly from its normal position.

35 When, subsequently, the member 21 is fully retracted by means of the retracting rod 24, to thereby readjust the element 27 to the normal position as described, the pin 45 will be carried out of engagement with the element 42 which will 40 then be returned to its normal retracted position by the spring 44. In the return movement of the member 21, however, the pin 45 will engage the inclined terminal surface 47 of the element 42 and will be permitted to return to the normal 45 position opposite the surface 46 of said element by pivotal movement of the said element in obvious manner. From the foregoing it will be apparent that any displacement of the element 27 from the normal position will result in an actuation of the switch 40, 42. This switch will be associated with the stop motion of the machine in such manner that the aforesaid actuation of the switch will in turn actuate the stop motion.

55 In accordance with the invention all of the retracting rods 24 of the assembly shown in Fig. 1 will be connected to a common actuator. This device is illustrated in Figs. 9 and 10 which shows a detector device having modified detector heads but being otherwise of the same general construction shown in Fig. 1. With reference to Figs. 9 and 10, therefore, the hub member 6 has mounted at the top thereof an annular element 51 in which is supported an apertured circular plate 52 for rotary movement about the axis of 60 the supporting rod 5. The plate 52 carries a series of upwardly projecting pins 53. Pivottally mounted on the annular member 51 is a plurality of bell crank levers 54, one for each of the associated detector heads, and these bell crank levers are connected respectively to the retracting rods 90 of the respective heads. The arms 55 of the bell cranks project inwardly over the outer edge of the plate 52 and into the path in which the pins 53 travel when the plate 52 is rotated. The arrangement is such that when

the said plate 52 is rotated clockwise, as viewed in Fig. 9, the pins 53 by engagement with the inner arms 55 of the respective bell crank levers will swing these levers in a direction to retract the rods 24 and the slide members of the associated detector heads to which the respective rods are connected. The plate 52 may be rotated manually through an arm 56 on the latter and an operating rod 57. It will be apparent that actuation of this arm to turn the plate 52 will result in a simultaneous retraction of the slide members 21 or equivalent member of the said heads.

The annular element 51 is insulated from the supporting hub member 6 in the manner illustrated in Fig. 11 wherein the insulating elements are indicated generally by the reference numeral 58. The circuit of the switch 41, 42 described above thus includes the supporting rod 8 extending from one of the terminal elements to the rounded hub member 6, and the retracting rod 24 extending from the other of said terminal elements to the ring 51 and thence through a lead wire 59 to the electrical actuating elements of the stop motion.

The modified detector head illustrated in Figs. 6, 7 and 8 is essentially the same as that described above with the exception that the spring 23 is replaced by a compression spring 61 which tends to urge the slide member 21 rearwardly to the fully retracted position indicated in broken lines in Fig. 6. A collar 62 on the support rod 8 limits this rearward movement of the slide. In order to normally retain the slide in the advanced position, a hook 63 is provided at the front of the element 27 which by interlocking engagement with the pin 36 holds the carriage in position against the pressure of the spring 61 so long as the element 27 is in the normal position. Angular displacement of the element 27 from this normal position, as described above, will release the hook 63 from the pin 36 and will permit the spring 61 to move the member 21 together with the detector fingers to the retracted position. In this rearward movement the switch 41, 42 will be actuated as described above.

During the retraction movement under action of the spring 61 the element 27 engages the abutment 39 or 41, as the case may be, which returns the element 27 to the normal position. When, under these circumstances, the slide member 21 is returned to the advanced position, the hook 63 will again interlock with the pin 36 to retain the member 21 in position against the pressure of the spring 61, the slight displacement of the element 27 as the hook 63 clears the pin 36 on the return movement being insufficient to entirely displace the spherical element 35 from the socket in the member 21 so that the element moves back immediately to the normal position wherein the hook is interlocked with the pin. It will be noted that in this case the rod 50, which corresponds to the rod 90 of the embodiment described above, will function to return the member 21 to the advanced position instead of retracting it and the connection between the rods 50 of the several heads and the common actuating plate 52 will be such that the pins 53 of that plate will force the rods 50 outwardly instead of retracting them, as in the embodiment shown in Figs. 2 to 5, when the plate is actuated.

In another embodiment, as shown in Figs. 9 to 16, inclusive, the finger supporting element 65 is pivotally mounted upon a member 60 slid-

ably supported on a fixed base 66, and a spring 67 associated with the pivot of the element 65 acts to retain the element in the normal position. Displacement of the element 65, occurring as described above by action of the moving fabric 68 when one or other of the detector fingers 69, 71 and 72 encounters a hole in the fabric, will be in opposition to the pressure of the spring 67.

The element 65 has a hook element 73 extending rearwardly therefrom which interlocks with a pin 74 when the element 65 is in the normal position. Pin 74 is mounted upon an element 75 which is slidably mounted on the slide 60 and which is urged rearwardly by an associated spring 76 supported in the slide. When the pin 74 is interengaged with the hook 73 the member 75 will be held in the retracted position, shown in Fig. 15, against the pressure of the spring 76. In this retracted position of the member 75 a recess 77 on the underside of the member registers with an aperture 78 in the slide 60 so that a spherical element 79 mounted in said hole may enter the recess 77 to occupy a relatively elevated position in said aperture. The sphere 79 is supported upon a spring arm 81 on the underside of the slide 60 which functions also as one terminal element of an electric switch, the other element 82 of the switch being the head of a bolt 83 which secures the base member 66 of the head to the supporting arm of rod 84. As shown in Fig. 15 insulating material 85 precludes electrical contact between the bolt 83 and the base member 66. A second screw 86 also serves to secure the base member 66 of the head to the support 85, and this screw is insulated by insulation means 49 from the support 84.

When the sphere 79 occupies the recess 77 the spring arm terminal element 81 will be elevated slightly above the terminal element 82 of the switch, as illustrated in Fig. 15. When the element 75 moves rearwardly under pressure of the spring 76 the sphere 79 will be moved downwardly so as to depress the spring arm 81 to an extent making contact between this arm and the terminal element 82 of the switch. The element 75 will be permitted to move rearwardly by action of the spring 76 only after the pin 74 is released from the hook 73. This release occurs when the element 65 is angularly displaced from its normal position as indicated in dotted lines in Fig. 12. When the hook releases the pin 74 the element 75 moves rearwardly to the position shown in Fig. 13 wherein the pin 74 still engages the outer end of the hook 73. Since the pin 74 does not move out of contact with the hook 73 the pin functions through the hook as a restraining stop for the element 65 under pressure of the spring 67. Thus when the element 75 is returned to the normal position the spring 67 will cause the element 65 to return to its normal position wherein the pin 74 lies at the inside of the hook 73.

Return of the element 75 from the retracted to the advanced normal position is effected by a rearward retraction of the slide member 60 through the medium of the retracting rod 90, see Fig. 9. A pin 87 extends upwardly from the support 84 in the path of this rearward movement and by engagement with the turned-down rear end of the element 75 will cause that element, as the member 62 is retracted, to return to the advanced normal position in which it is shown in Fig. 15. This adjustment of the element 75 not only permits the element 65 to return to the normal position but also permits the spherical element 79 to pass into the recess 77 so that the switch arm

may flex upwardly out of contact of the element 82. Retraction of slide member 60, as described above, occurs against the pull of a spring 48, see Fig. 14, secured to the base member 66 and to the rear end of the member 60, as illustrated, and which functions to return the member to the normal advanced position when retracting rod 90 has been released.

In the embodiment of the invention shown in Figs. 18 to 22 inclusive, the detector finger support element 91 is pivotally mounted, as indicated at 92 in Fig. 21, upon a member 93 which is slidably supported in the base 94 of the head. In this instance the base 94 is secured to the supporting element 95 by screws 96, 96 which are both insulated, by means shown at 97 in Fig. 21, from the support elements so that the base 94 is normally electrically disconnected from said support. The slide member 93 is normally retained in an advanced position by means of a spring 98 connected at 99 to the front of the base, and at its rear end to a depending arm 101 on the slide member 93. The member 93 may be retracted against the action of the spring 98 by a retracting rod 102 of the character previously described.

In the normal advanced position of the member 93, and when the element 91 also occupies the normal position as determined by the spring pressed elements 103, the forward recessed face 104 of the element 91 is spaced apart from a pin 105 which extends upwardly from the support element 95. When the element 91 is angularly displaced from its normal position, as by means previously described, one or other of the forwardly projecting portions 106 of the said forward face 104 at the opposite sides respectively of the recesses will be brought into contact with the pin 105, as illustrated in Fig. 23. In this case the pin 105 forms one terminal element of an electric switch and the element 91 the other, so that when the latter element is displaced the switch will be closed to thereby actuate the stop motion of the machine in which the detector head is installed. Following such actuation the element 91 may be rotated to its normal position by retracting the member 93 to an extent bringing the side of the element 91 into engagement with one or other of the abutments 107 and 108 at the opposite sides of the base member 94 as illustrated for example in Fig. 20, the continued retraction of the slide 93 forcing the element 91 to turn to the normal position. When the slide member 93 is then released and is returned by action of the spring 98 to the normal advanced position the element 91 will occupy its original spaced relation to the pin 105.

The embodiment of Fig. 24 corresponds generally to that of Fig. 9 with the exception that in this case the retracting rods 106 (which correspond to the rods 90 of the embodiment of Fig. 9) are pivotally connected directly to the rotary plate 107 (plate 52 of Fig. 9) so that the bell cranks 54 of the earlier embodiment are eliminated.

The construction illustrated in Figs. 25 and 26 affords a materially more compact assembly than those illustrated in the preceding figures. In this case detector heads 110, 111, 112 and 113 are mounted respectively upon arms 114, 115, 116 and 117 which extend radially from a hub 118 suitably secured to the supporting rod 119. The retracting rods 121, 122, 123 and 124 which correspond to the rods 24, 90 and 106 of the previously described embodiments and which are associated respectively with the detector heads 110, 111, 112 and 113 are pivotally connected at the points 125, 75

126, 127 and 128 to a sleeve 129 which is mounted upon the upper end of the hub 118 for angular movement about the rod 119. The sleeve 129 is provided also with an arm 131 to which is connected a rod 132 by means of which the sleeve 129 may be rotated to retract the detector elements of the respective heads in the manner previously described.

We claim:

1. In a detector device of the character described, a detector head comprising a base, a member slidably supported in said base, a spring attached to said member and to the base and tending to retain the member in an advanced position on the base, means for retracting the member in opposition to the spring, a spring-pressed detector finger, a pivoted element slidably supporting said finger and means for releasably retaining said element in a predetermined normal position on the pivot, an electric switch, and means for operatively connecting the switch and pivoted element so that the switch is actuated by angular displacement of the said element from the normal position, and means responsive to retraction of said member for returning the said element to the normal position.
2. A detector head according to claim 1, wherein the finger supporting element is supported on the slide member.
3. A detector head according to claim 2, wherein the switch elements are mounted on the base, a switch actuating element carried by the slide member and operative to actuate the switch upon a partial retraction of said member, and means including a fixed abutment for the finger-supporting element for so partially retracting the slide member when the said supporting element is displaced from the normal position.
4. A detector head according to claim 3 wherein in a spring is operatively connected with the switch and tends to retain the switch elements in predetermined relative position, said switch actuating element moving one of the said elements against the action of the spring to actuate the switch.
5. A detector head according to claim 1 wherein in the said switch comprises contact elements on the base and finger-supporting element respectively, said elements being relatively moved to actuate the switch when the said supporting element is displaced from the normal position.
6. A detector head according to claim 1 wherein in the finger-supporting element is mounted on the slide member, a spring being provided to retain the element in the normal position, a switch control member, a spring tending to move said control member to an extended switch actuating position, and means on said control member operative in the extended position of the latter to retain the finger-supporting element in a position displaced from the normal against action of the spring tending to return said element to the normal position.
7. A detector head according to claim 6 wherein interlocking means is provided upon the finger-supporting element and control means and operative only when the said element is in the normal position to lock the control member in a retracted position.
8. A detector head according to claim 7 wherein means is provided for moving the control member from extended to retracted position when the slide member is retracted.
9. A detector head according to claim 8 wherein in the switch is open when the control member

is retracted and closed when the said member is extended.

10. In a detector device of the character described, the combination with a plurality of detector heads arranged in relatively spaced annular series, each said head comprising at least one longitudinally movable detector finger disposed approximately radially to the center of the annulus defined by said heads and resilient means for urging the finger toward an advanced position, a member movable approximately radially with respect to the center of said annulus and means for normally retaining said member in an advanced position relatively remote to said center, means for pivotally supporting the detector finger on said member for angular movements approximately in the plane of said annulus, means for releasably retaining the finger in a predetermined normal position with respect to said angular movement, means for returning the finger to the normal position following angular displacement, said return means including means for retracting the movable finger-supporting member together with relatively fixed finger-deflecting means located in the path of the finger when re-

tracted with said member, and a common actuator for the said retracting means of all of said heads.

11. A detector device according to claim 10 wherein the common actuator for the retracting means includes a single actuator member angularly movable about the center of the said annulus.
